Primary Examiner — Elizabeth J Oswecki(74) *Attorney, Agent, or Firm* — Loren Donald Pearson; Assouline & Berlowe, P.A.(57) **CLAIM**

The ornamental design for a bottle, as shown and described.

DESCRIPTION

FIG. 1 is a first perspective view of a bottle showing my new design in a closed configuration;

FIG. 2 is a second perspective view thereof;

FIG. 3 is a front side view thereof;

FIG. 4 is a rear side view thereof;

FIG. 5 is a right side view thereof;

FIG. 6 is an exploded left side of a bottle in an open configuration;

FIG. 7 is a top plan view of a bottle in a closed configuration; and,

FIG. 8 is a bottom plan view thereof.

The diagonal line shading represents a reflective, opaque surface on a thick-walled, tinted glass bottle and the linear line shading represents the curvature of the bottle.
